LAMP.

Filed Dec. 10, 1927

UNITED STATES PATENT OFFICE

LOUIS EDWARD PERKINS, OF RICHMOND HILL, NEW YORK, ASSIGNOR TO PERKINS MARINE LAMP CORPORATION, OF BROOKLYN, NEW YORK, A CORPORATION OF NEW YORK

LAMP

Application filed December 10, 1927. Serial No. 239,095.

This invention relates to lamps, and is more particularly directed to improved lantern globes and mountings therefor.

An object of this invention is to provide 5 a lantern globe for a portable or marine lamp, said globe being provided with novel closure means permitting ready access to the interior of the lamp for safe and easy manipulation or removal of the light providing 10 means, while at the same time preserving at its maximum the uniform lighting quality and usefulness of the lamp.

A further object of the invention is to provide a lantern having a globe of the character 15 set forth, and improved means for mounting said globe in a simplified manner and for affording a rugged construction.

A still further object of the invention is to provide a lantern of the character described 20 of improved construction, comprising few and simple parts which are assembled to form a structure of neat appearance, which lantern shall be relatively cheap to manufacture, and practical and efficient to a high degree 25 in use.

Certain features herein shown and described are shown, described and claimed in my co-pending application Serial No. 165, 30 357 filed February 2, 1927, and accordingly 30 are not claimed herein.

Other objects of this invention will in part be obvious and in part hereinafter pointed out.

The invention accordingly consists in the 25 features of construction, combinations of elements, and arrangement of parts which will be exemplified in the construction hereinafter described, and of which the scope of application will be indicated in the following claims.

In the accompanying drawing, in which 40 is shown one of the various possible illustrative embodiments of this invention,

Fig. 1 is a view in elevation of a lantern embodying the invention, parts being broken away to show the method of mounting the globe and lighting unit therein;

Fig. 2 is a view in section taken on line 45 2-2 of Fig. 1, parts being broken away to show the mounting of the globe sections in 50 their respective frames.

Fig. 3 is a fragmentary cross-sectional view showing the closure member partly swung to open position, and with portions broken away to show the method of mounting a globe section. 55

Figs. 4 and 5 are elevational views of the fixed and movable portions of the globe, taken in the direction of the arrows 4-4 and 5-5 of Fig. 6, respectively, with part of the frame for mounting such portions attached, and further showing the abutting edge construction of the globe portions; and 60

Fig. 6 is a top plan view showing an end of an assembled globe.

While the invention may be applied to 65 lighting devices using oil, gas, or electricity, the lantern disclosed herein, as shown, is of the oil burning type, adapted particularly for marine service.

Referring in detail to the drawing, the lantern embodying the invention there shown comprises a casing H, and a tubular globe formed preferably with a "Fresnal" type lens L formed of thick glass. Said casing H includes a cylindrical supporting receptacle 10 arranged to receive coaxially therein an oil fount 11 having a conventional burner B. Openings 12 in the wall of said receptacle permit the entrance of air, while openings 13 in the hood 14 of the casing provide an outlet for 70 said air. The top portion of hood 14 of the lantern and said receptacle 10 are firmly interconnected by spacing rods 16 which have their 75 ends secured by means of screws 19 to clamp flanges 17 and 18 of said hood and receptacle respectively. A ring handle 15 is conveniently positioned at the top of the lantern. 80

The globe or lens L is of tubular cylindrical form and comprises the two semi-cylindrical portions 22 and 23, the edges of which 85 abut as at 20 and 21 to present the form of a cylindrical lens. Portion 23 is fixed with respect to casing H, while portion 22 provides a movable closure for the casing which may be 90 swung to an open position to allow ready access to the interior of the lamp whenever necessary, as for example, to permit removal and replacement of the oil fount and burner, thus facilitating filling, cleaning or adjustment without the inconvenience of tipping 100

the fount and avoiding accidental spilling of oil.

The portion 23 of the globe is stationary, being fixed in position by upper and lower arcuate frame members 24 which are secured between the ends of the rods 16 and the clamp flanges 17 and 18 as shown in Fig. 1. Said stationary portion 23 may abut, on its inner surface along its circular edge, against rings 25 which extend down into the globe from the hood 14 and up from receptacle 10 of the lantern. Preferably the globe portion 23 is undercut along its flat, curved-shaped edges to provide a semi-annular projection 26, at the upper and lower ends of the portion 23, the inner edges of the arcuate frame members 24 being received against this ring and fitting tightly against the faces 23^a and 26^a presented by the undercut construction. In this manner, the projections 26 are rigidly retained between the frame members 24 and the rings 25.

The movable lens portion 22 forming the closure or door is mounted upon a frame F including upper and lower horizontally extending arcuate members 27, joined by connecting rods 28, screws 28' received in rods 28 and having their heads countersunk into members 27 providing means for fixing the relation of these several parts. The frame F is thus adapted for a snug and slidable fit between the clamp flanges 17 and 18 so that by making this frame of proper height to contact the inner edges of the members 27 against the rings 25, a draft-tight apparatus will be presented.

The closure portion 22 of the globe is undercut along its flat, curved-shaped edges 22^a to provide the arcuate projection 30, while the frame members 27 are formed with curved recess slots 31, bounded at the ends thereof by sides 32, the projections 30 being cut away at 32^a at said side to provide space therefor. It will thus be seen that the closure portion 22 of the globe is reliably secured in the movable frame of the lantern, and in a simplified and improved manner. As shown in Figs. 2 and 3, the door frame F carrying globe portion 22 is provided with a projection or pivot portion 27^a received on one of the rods 16, as at 16^a.

The projection 27^a is so positioned on frame member 27 as to allow proper rotation of the door frame with respect to the fixed portion 23. Each of said fixed members 24 is provided with a cut out 24^a for properly receiving projection 27^a to allow pivotal movement of the several parts.

As can be seen in Fig. 1, the projections 30 of the movable globe portion are of less height than projections 26 of the stationary globe portion, thus ensuring the desired clearance at the clamp flanges 17 and 18. When the swingable closure is in locked position, as shown in Fig. 2, it is substantially

draft-tight at the upper and lower edges of the movable globe portion 22. Locking devices such as pivoted latches 33 are provided at the end of members 27 removed from pivot rod 16^a for engaging related parts on the frame members 24.

To make a draft-tight joint between the split portions of the globe, the vertically extending edges of the fixed and movable globe portions are formed with stepped joints or mating rabbets 23^c and 22^c, respectively. Preferably the rabbets 23^c of the stationary globe portion are formed to be received within the rabbets 22^c of the movable globe portion. Thus said rabbets constitute a reliable means for aiding in the alinement and coaction of the globe portions, providing extended surface contact to make the globe draft-tight, and increasing resistance to any draft leak at this point.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A lantern of the character described, comprising a globe split longitudinally to provide a stationary and a movable portion, means to support said stationary portion including arcuate members extending along the upper and lower edges of said stationary portion, and a frame to support said movable portion between said members, said movable portion being less in length than said stationary portion.

2. In a lantern of the character described, a globe having a plurality of relatively movable portions, and a frame to support one of said portions, said frame having a recess, said portion of the globe having a securing projection undercut at the ends thereof to be received in said recess.

In testimony whereof I affix my signature.

LOUIS EDWARD PERKINS.
